TOY LAWN SWING

John W. Ryan, Bel Aire, Calif., assignor to Mattel, Inc., a corporation of California

Filed Apr. 3, 1964, Ser. No. 79,328

Term of patent 14 years

(Cl. D34—5)

Fig. 1

I claim:

The new and ornamental design for toy lawn swing, substantially as shown.
